Primary Examiner — John R Yeh

Assistant Examiner — Dustin Andrew Griffith

(57) **CLAIM**

The ornamental design for a casual bag, as shown and described.

DESCRIPTION

FIG. 1 is a perspective view of a casual bag design showing my new design.

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.

The broken lines in the figures depict portion of the causal bag that form no part of the claimed design. The broken lines showing stitching in the figures also forms no part of the claimed design.

1 Claim, 7 Drawing Sheets
